GAME APPARATUS

David C. Rockola, Chicago, Ill.

Application August 28, 1935, Serial No. 38,164

2 Claims. (Cl. 116—114)

This invention relates to a game apparatus.

It is an object of this invention to provide an improved game apparatus which is relatively simple and inexpensive in construction and efficient in use.

Another object of the present invention is to provide a tell-tale device which is particularly adapted for use in conjunction with coin-controlled amusement game apparatus to indicate to the proprietor or owner thereof when the player has attempted to operate the same fraudulently by moving the apparatus from its proper operating position.

Another object of the invention is to provide, in a game apparatus, the invention hereinafter described and claimed.

Other objects will appear hereinafter.

The invention consists in the novel combination and arrangement of parts to be hereinafter described and claimed.

The invention will best be understood by reference to the accompanying drawing, showing the preferred form of construction and in which:

Fig. 1 is a front elevational view of a game apparatus embodying a preferred form of the new tell-tale device;

Fig. 2 is a horizontal sectional view on line 2—2 in Fig. 1;

Fig. 3 is a vertical sectional view on line 3—3 in Fig. 1;

Fig. 4 is a vertical sectional view on line 4—4 in Fig. 3; and

Fig. 5 is a sectional detail view on line 5—5 in Fig. 3.

35. A game apparatus embodying a preferred form of the new tell-tale device is illustrated in the drawing, is therein generally indicated at 10, and comprises a cabinet or casing 11, in which is arranged a supporting frame 25 for the new tell-tale device, and provided in the top wall 12 of the cabinet or casing 11 is a coin slot 13.

Pivottally journalled in the cabinet or casing 11 is a horizontal shaft 14 which carries a handle 15 that is disposed exteriorly of the cabinet 11 45 adjacent the front wall 16 thereof.

Provided in the front wall 16 of the casing 11 is a transparent window 17 and pivottally mounted between its ends in the cabinet 11, as at 18, and rearwardly of the sight opening or window 50 17, is a U-shaped tell-tale member 19 which includes parallel arms 23 and 61 and an indicium-bearing cross arm 20 which extends between said arms 23 and 61. This member 19 is counterbalanced so that the end portion or cross arm 20 is 55 normally urged by gravity into alignment or reg-

istration with the window 17 (clockwise, from dotted to full line position, Fig. 3).

Pivottally suspended in the cabinet 11, at a point 21 above the tell-tale member 19, is a pendulum 22 and when the cabinet 11 is in its proper operating position, that is, with the base of the same horizontal, the pendulum 22 will hang in vertical position (as in dotted lines, Fig. 4) and in this position of the pendulum the same bears at its lower end against the tell-tale member 19 and thereby maintains the latter in an inclined position (as in dotted lines, Fig. 3) so as to dispose the indicium-bearing portion 20 thereof out of registration with the sight opening 17. However, if the cabinet or casing 11 is, for any reason, tilted out of its proper operating position, in an attempt to operate the same fraudulently or for any other reason, the pendulum 22 will assume a tilted position (for example as illustrated in full line position, Fig. 4 with its lower end disposed 10 between the parallel sides or arms 23 and 61 of the tell-tale member 19), whereupon the tell-tale member 19 will pivot by gravity (clockwise, from dotted to full line position, Fig. 3), thereby disposing the indicium-bearing cross-arm 20 of the 15 tell-tale member 19 in registration with the sight opening 17 to indicate that the cabinet 11 has been tilted from its proper operating position.

Provided in the cabinet 11 is a device generally indicated at 24 for resetting the pendulum 22 and the tell-tale member 19 back into their initial positions, and into latching engagement with each other, after operation thereof; this resetting device 24 being associated with the coin slot 13 and being controlled by a coin inserted into the 35 same.

Arranged in the cabinet 11 is a frame 25 and pivottally mounted in this frame 25, as at 26, is a member 27 which has a laterally extending arm 28 which is provided on its lower edge with a rack 40 or series of teeth 29. The member 27 is urged in a clockwise direction, into full line position (Fig. 4), by a spring 40, and arranged below the arcuate arm 28 of the member 27 is an arcuate trackway 59.

The arm 28 of the member 27 works in a transverse slot 30 which is provided in a coin receptacle 31 which is arranged below the coin slot 13 and in communication therewith (Figs. 3 and 4).

The coin receptacle 31 is formed as a part of 50 an upright member 32 which is pivottally mounted between its ends on the shaft 26 and this member 32 has a downwardly extending or angled end portion or arm 33 which is adapted to be projected under the arm 61 of the tell-tale mem- 55

ber 19 (Figs. 3 and 4). The member 32 is urged in a clockwise direction, into full line position (Fig. 4) by a spring 60.

The shaft 14 has an angled end portion or arm 34 and pivotally attached to this arm 34, as at 35, is one end portion of a link 36, the other end portion of the link 36 being pivotally attached, as at 37, to an arm 38 of the member 27.

Having one end attached to the member 27, as at 39, is a resetting spring 40, the other end of which is attached, as at 41, to a supporting arm 42 which is arranged in the cabinet 11.

Pivotedly mounted in the cabinet 11, as at 43, upon a supporting member 44, is a two-way so-called full stroke dog 45 which is engageable with the teeth 29 of the arm 28.

Carried by the member 32 is a laterally projecting pin or lug 46 which is engageable in a notched portion 47 of a latch arm 48 which is pivotally mounted, adjacent one of its ends, in the cabinet 11, as at 49 (Fig. 4), and the member 27 has an arm 50 which is provided with a lateral extension 51 which is engageable with the latch arm 48 adjacent the end thereof which is opposite the end of the same that is pivotally mounted, at 49, in the cabinet 11 (Fig. 4).

Pivotedly journaled in the cabinet 11, is a horizontal shaft 52 on which is mounted a disc 53 which is visible in the cabinet 11 behind a transparent window 54 provided therein. Mounted on the shaft 52 is a ratchet 55 and urged into engagement with the ratchet 55 by a spring 56 is a pawl 57 which is pivotally mounted upon the member 32.

Operation

When the cabinet 11 is in its proper operating position, with the base thereof horizontal, the pendulum 22, hanging in a vertical position, rides upon the arm 61 of the tell-tale member 19 and keeps the latter in a tilted position, that is, out of horizontal position (as in dotted lines, Fig. 3), so that the tell-tale indicium on the cross arm 20 of the tell-tale member is out of registration with the sight opening 17 and not visible therethrough.

However, if the cabinet 11 is tilted from its proper operating position, for any reason, such as by an attempt of the player to operate the game apparatus fraudulently, the lower end of the pendulum 22 rides off the arm 61 of the tell-tale member 19, whereupon the counterbalanced end portion or cross arm 20 of the tell-tale member 19 pivots by gravity into position (as in full lines, Fig. 3) to dispose the tell-tale indicium on the cross arm 20 of the tell-tale member in registration with the sight opening 17 so as to indicate that the apparatus has been tilted from its proper operating position; and the tell-tale member 19 remains in this effective position (as in full lines, Fig. 3) until such time as a proper coin is inserted into the apparatus and the latter is operated.

When a coin is inserted into the coin slot 13 it falls by gravity into the coin receptacle portion 31 of the upright member 32 and when in this position the coin bears at its lower edge upon the trackway 59.

The operator then presses downwardly upon the handle 15, moving the same from full to dotted line position (Fig. 1). This movement of the handle 15 moves the shaft 14 and its angled end or arm 34 (counterclockwise, from full to dotted line position, Fig. 4) and this movement of the shaft 14 and its arm 34 acts through the link 36 to pivot the member 27 (counterclockwise, from full to dotted line position, Fig. 4). This

movement of the member 27 projects the arm 28 thereof through the right hand slot 39 which is formed in the coin receptacle 31 (right to left, Fig. 4) and, at the start of this movement, the outer end of the arm 28 engages the coin which is disposed in the coin receptacle 31, whereupon, as the member 27 and its arm 28 continue to move (counterclockwise, or right to left, Fig. 4), the coin receptacle 31 and its carrier or supporting member 32 are likewise moved (counterclockwise, or right to left, Fig. 4), thereby moving the coin, which is disposed in the coin receptacle 31, along the trackway 59 to the left hand end thereof, as seen in Fig. 4, whereupon the coin 62 drops off the trackway 59 into a suitable receptacle 15 which may be provided therefor in the cabinet 11.

During the foregoing movement of the coin carrier 32 and its coin receptacle portion 31 (counterclockwise, from full to dotted line position, Fig. 4) the downwardly angled end portion or arm 33 of the coin carrier 32—31 engages the arm 61 of the tell-tale member 19 and thereby pivots the tell-tale member 19 (counterclockwise, from full to dotted line position, Fig. 3); thus moving the indicium-bearing portion or cross-arm 20 of the member 19 out of registration with the sight opening 17 whereupon the pendulum 22 will swing into a vertical position, (as shown in dotted lines, Fig. 4), and the bottom end thereof will latchingly engage the arm 61 of the U-shaped tell-tale member 19 thereby holding the end portion or cross arm 20 thereof out of registration with the sight opening 17.

As the member 27 and its arm 28 and the coin carrier 32 and its receptacle 31 are thus moved (counterclockwise, from full to dotted line position, Fig. 4) the dog 45 rides over the ratchet teeth 29 which are formed on the bottom edge of the arm 28, and when the member 32 reaches the end of its operative stroke (as in dotted lines, Fig. 4) the notched portion 47 of the latch arm 48 falls upon the pin 46 and prevents retroactive movement of the member 32, pawl 57, ratchet 55, and disc 53 until the member 27 and its arm 28 have reached the end of their operative stroke and are disposed as in dotted line position, Fig. 4, whereupon the two-way full-stroke dog 45 reverses its position and releases the member 27 and its arm 28 for retroactive movement (clockwise, from dotted to full line position, Fig. 4); the member 27 and its arm 28 then being reset or pivoted (clockwise, Fig. 4) by the resetting spring 40.

It is to be noted in this connection that the purpose of the full-stroke dog 45 is to compel the operator of the device to move the member 27—28 a full stroke (counterclockwise, from full to dotted line position, Fig. 4) before the dog 45 can be reversed and the member 27—28 returned to its initial position, as in full lines, Fig. 4.

When the member 27 and its arm 28 reach their initial position (as in full lines, Fig. 4), the lateral extension 51 of the arm 50 of the member 27 engages under the left hand end portion of the latch arm 48 (as seen in Fig. 4), thereby pivoting the latch member 48 (clockwise, from dotted toward full line position, Fig. 4). This movement of the latch member 48 releases the notched portion 47 thereof from latching engagement with the pin 46 which is carried by the coin carrier 32, whereupon the then tensioned resetting spring 60 acts upon the coin carrier 32 and its coin receptacle 31 to pivot the same back into its initial position (clockwise, from dotted to full line position, Fig. 4); and during this movement of the

member 32 the pawl 57 carried thereby (Fig. 5) engages the ratchet 55 and thereby rapidly rotates the ratchet 55, shaft 52, and the disc 53 (counterclockwise, as seen looking from right to left, Fig. 3, at the front wall of the cabinet 11).

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

15 Thus, for example, while I have shown and described the new tell-tale device as preferably used in conjunction with a game apparatus, it is to be understood that it may be used in conjunction with other devices, machines or apparatus in connection with which it may be desired to indicate when the same are, and are not, in proper or normal operating position.

Having thus described my invention, what I claim as new and desire to protect by Letters 20 Patent is:

1. In a game apparatus, the combination of: a cabinet having a sight opening provided therein; a tell-tale member movably mounted in said cabinet and having an indicium-bearing portion; 25 a pendulum in said cabinet normally engaging the said tell-tale member and holding the same in position to dispose the said indicium-bearing portion thereof out of registration with said sight opening when the said cabinet is in its proper or

normal operating position; said pendulum moving out of engagement with the said tell-tale member so that the said indicium-bearing portion thereof may move into registration with the said sight opening, if and when the said cabinet is moved or tilted from its normal or proper operating position; a disc rotatably mounted in the said cabinet and having a portion visible through the said sight opening; and means for rotating the said disc including a device for resetting the 10 said tell-tale member and the said pendulum into engagement with each other.

2. In a game apparatus, the combination of: a cabinet having a sight opening provided therein; a tell-tale member movably mounted in said cabinet and having an indicium-bearing portion; 15 a pendulum in said cabinet normally engaging the said tell-tale member and holding the same in position to dispose the said indicium-bearing portion thereof out of registration with said sight opening when the said cabinet is in its proper or normal operating position; said pendulum moving out of engagement with the said tell-tale member, so that the said indicium-bearing portion thereof may move into registration with the said sight opening, if and when the said cabinet is moved or tilted from its normal or proper operating position; a rotatable disc in the said cabinet; and means for operating the said disc; said 20 means including a device for resetting the said tell-tale member and pendulum into engagement with each other.

DAVID C. ROCKOLA.
